J. B. HALLER

TENNIS COURT MARKER

Filed May 25, 1922

Inventor
J. B. Haller

Attorney
A. B. Anthony

UNITED STATES PATENT OFFICE.

JULIAN B. HALLER, OF WYTHEVILLE, VIRGINIA.

TENNIS-COURT MARKER.

Application filed May 25, 1922. Serial No. 563,623.

To all whom it may concern:

Be it known that I, JULIAN B. HALLER, a citizen of the United States, residing at Wytheville, in the county of Wythe and State of Virginia, have invented certain new and useful Improvements in Tennis-Court Markers; and I do hereby declare the following to be a full, clear, and exact description of the invention, such as will enable others skilled in the art to which it appertains to make and use the same.

The invention has relation to a device for marking tennis courts and has for its object the provision of a device of the nature and for the purpose stated which will admit of the marking drum being easily and readily supplied with the marking material without causing any inconvenience or annoyance.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a top plan view of a tennis court marker embodying the invention, the drum being in section and the outer portion of the handle broken away,

Figure 2 is a perspective view of the device, the cover being open and the drum in position to receive a charge of marking material, and

Figure 3 is a sectional detail of the drum and parts associated therewith.

Corresponding and like parts are referred to in the following description and designated in the several views of the drawings by like reference characters.

The marking drum comprises a circular wall 1 which is perforated for the discharge of the marking material such as air slaked lime, marble dust or the like, a circular head 2 secured to one side of the wall 1 and an inner flange 3 attached to the opposite side of the wall 1 and flared towards its inner edge in an outward direction. Beads or flanges 4 are provided at opposite sides of the wall 1 and serve in a measure to stiffen and reinforce the drum and support the

same when trundled over the ground. A threaded stem 5 is supported centrally in the head 2 and projects outwardly therefrom to provide a journal 6. A cover 7 closes the open side of the drum and its marginal portion fits close against the flange 3 and snugly within the bead 4 at the outer edge of said flange 3. The cover 7 is outwardly dished to correspond with a like dish of the head 2 with the result that the sides of the drum are symmetrical and outwardly bulged. A hollow screw 8 is secured near its outer end to the cover 7 by means of a swivel joint and its outer end terminates in a finger piece for convenience of rotating the screw by hand. The hollow screw 8 matches the threaded stem 5 and coacts therewith to secure the cover 7 when fitted to the drum to close the open side thereof. The hollow screw 8 projects beyond the outer side of the cover 7 to provide a journal 9 to serve as means for attaching the cover to the handle. The hollow screw 8 and threaded stem 5 constitute parts of an axle by means of which the drum is pivoted to the handle.

The handle comprises a socket 10 and a pole or stick 11 fitted thereto. An arm 12 projects from the socket 10 and receives the journal 6 of the drum. An arm 13 is pivoted at 14 to the socket and its outer end receives the journal 9. The arms 12 and 13 are spread and constitute elements of a fork, between which the marking drum is journaled. As shown most clearly in Figure 2, the drum is carried by the arm 12 and the cover by the arm 13. When the hollow screw 8 is disengaged from the threaded stem 5, the cover 7 may be swung into open position thereby admitting of the marking material being easily and quickly supplied to the drum without any inconvenience or annoyance. After the drum has been charged, the cover is swung into closed position and made secure by threading the hollow screw 8 upon the threaded stem 5.

What is claimed is:

1. A tennis court marker comprising a marking drum having a perforated band periphery and an open side, a removable cover for closing the open side of the drum, means for securing the cover in closed position, and a handle including a fork, one of the members of which is pivoted and the drum and cover being journaled to the respective fork members.

2. A tennis court marker comprising a marking drum having a perforated band periphery and an open side, a removable cover for closing the open side of the drum, means for securing the cover in closed position, said means constituting an axle by means of which the drum is pivotally mounted, and a handle including a fork, one of the members of which is pivoted and the drum and cover being journaled to the respective fork members.

3. A tennis court marker comprising a marking drum having a perforated band periphery and an open side, a removable cover for closing the open side of the drum, and

means for securing the cover in closed position, said means consisting of a sectional axle, each of the sections being applied to the respective parts and said sections having screw thread connection, and a handle including a fork, one of the members of which is pivoted and the drum and cover being journaled to the respective fork members. 20

In testimony whereof I affix my signature in presence of two witnesses.

JULIAN B. HALLER.

Witnesses:

CHARLES FOX GRAHAM,
B. M. WOLFENDEN.
